UNITED STATES PATENT OFFICE.

JOHN E. GARRETT, OF NEW GLASGOW, NOVA SCOTIA, CANADA.

MACHINE FOR MAKING RUGS.

No. 889,922.

Specification of Letters Patent.

Patented June 9, 1908.

Application filed May 8, 1907. Serial No. 372,487.

To all whom it may concern:

Be it known that I, JOHN E. GARRETT, a citizen of the Dominion of Canada, resident of New Glasgow, in the county of Pictou and 5 Province of Nova Scotia, Canada, have made a certain new and useful Invention in Machines for Making Rugs; and I declare the following to be a full, clear, and exact description of the same, such as will enable others 10 skilled in the art to which it appertains to make and use the invention, reference being had to the accompanying drawings, and to letters or figures of reference marked thereon, which form a part of this specification.

15 Figure 1 is a perspective view of the invention showing the lance and looper blade in projected position with the lance partially withdrawn. Fig. 2 is a central longitudinal section on the line 2—2, Fig. 5, showing the 20 first and last position of the parts in the operation of the device, with the lance slide or holder and lance withdrawn. Fig. 3 is a side view of the invention with the parts in the position shown in Fig. 2. Fig. 4 is a side view of 25 the same showing the second position of the parts, with the lance and looper blade projected. Fig. 5 is a front view of the invention partly broken away. Fig. 6 is a cross section of the line 6—6, Fig. 2.

30 The invention has relation to hand looping machines for making rugs or mats, and it consists of the novel construction and combination of parts, as hereinafter set forth.

35 The object of the invention is to provide a simple and strong instrument for the purpose, which will have a positive feed.

In the accompanying drawings, illustrating the invention, the letter *a*, designates a 40 hollow handle having a chamber *b*, in which is located a spring *c*, which engages a reciprocating stem or shank *d*, which extends out of the chamber through an opening *e*, in the cap *f*. To the handle and cap is rigidly secured a bracket *g*, which holds a spring arm carrying frame *h*, having a presser foot *k*. The carrying frame *h*, extends parallel to the stem *d*, for a certain distance, beyond which it is deflected outward and forward to the presser foot, as indicated at the incline or slant *m*.

45 Having movement upon the carrying frame is a sliding holder *p*, consisting of a longitudinal plate or bar portion *s*, having at its inner end a transverse finger piece or operating flange *t*, which is provided with an aperture *v*, through which passes the stem *d*, on which this sliding holder is designed to have

reciprocating motion. At its outer end the sliding holder *p*, is provided with an inward extending clamp arm *u*, whereby the tubular lance *z*, is attached at its rear end to the 50 holder, said lance being rigidly secured in place by a clamp screw *2*.

To the end of the stem *d*, is secured the looping blade *n*, which extends into the tubular lance, and operates in connection therewith. 65 To the forward end of the stem *d*, is secured a bearing piece *3*, which engages the carrying frame *h*, and serves to steady the same, while the latter acts as a guide and bearing to prevent any rotary movement of said stem. 70

The upper surface of the stem is provided with a longitudinal groove at *4*, in which is secured a small steel strip spring *5*, the end of which is bent upward in an inclined manner to provide a catch *6*. This catch is designed to project out of the groove sufficiently to engage the margin of the opening *e*, in the cap *f*, when the stem is pushed outward from the chamber in the handle far enough to carry said catch beyond said opening. This 80 catch is released by means of the aperture *v*, in the finger piece *t*, when the latter is pulled backward against the end of the cap, so that the spring can retract the stem and looper blade. 85

In the construction shown the carrying frame *h*, is made of steel wire and has two branches *7*, the ends of which engage bent flanges *8*, of the bracket *g*, and are clamped thereto by means of a clamp nut *9*, and a 90 screw engaging the same. The clamp nut engages the broad cheeks *g'* of the U-shaped bracket and is thereby prevented from turning when the clamp screw is tightened.

At the forward ends of the branches *7*, of the carrying frame *h*, the presser foot *k*, is formed of the wire of such frame, this presser foot portion extending transversely just in front of the point of the lance. The end of the presser foot is reversely bent as at 11, and the transverse portions *12*, are straight or nearly so and at right angles to the lance when the latter is in retracted position. The body portion *s*, of the slide *p*, overlaps the carrying frame at each side, the head of the 100 clamp screw *2*, also overlapping such frame at one side, said body portion and screw head having sufficiently close engagement with said frame to deflect the slide and lance carried thereby away from the end 11, of the 105 presser foot when in projected or protruded position, owing to the inclines *m*, of the 110

branches of the carrying frame. As the presser foot is serrated to provide for frictional contact with the fabric which is being turfed, the foot will have a positive feed in the direction of its length at every stroke of the lance.

The operation is as follows: The fabric, which may be a piece of burlap or other coarse cloth, is stretched upon a frame. 10 Then the operator after threading the tubular lance with a strip of rag or carpet yarn, holds it over the cloth by grasping the handle in his right hand. The presser foot is designed to be held in engagement with the 15 cloth, and the finger piece being then pressed down against the bearing piece of the looper stem *d*, causes the lance slide or holder *p*, to carry the lance through the fabric with the attached cloth strip or yarn. Normally, the 20 looper blade, which is of spring steel, is exposed behind the open rear end of the tubular lance, and extends into the same to within about half an inch or so of the point. And as the end of the looper blade is concave or 25 provided with projections *r*, to engage said strip or yarn, it serves when the finger piece is drawn back, withdrawing the lance from the fabric, to hold a loop of the cloth strip or 30 yarn in position on the under side of the fabric. And when the finger piece is brought against the end of the cap *f*, the looper stem is released, and the spring in the hollow handle acts to jerk the looper back into retracted 35 position in the lance, leaving the cloth or yarn loop in position on the other side of the fabric. This operation having served to advance the presser foot a little, the instrument is operated to form another loop. In this 40 manner the piling can be effected in a very rapid and uniform manner and if the base cloth is marked with a design, a figured rug may be easily and quickly made.

As the hollow lance or needle is entirely open in the rear it can be threaded with great 45 facility, the material being entered at its open end, above the looper blade. Much time is saved in this way, and when it is considered that mats and rugs of this kind are made in many cases from a large number of 50 short strips, this is a matter of importance. Furthermore the threading path is smooth and is provided with a guide in the looper blade, so that the liability of breaking delicate or weak strands or strips of cloth such 55 as are for the most part used up in work of this kind, is very much reduced.

The tubular lance is adjustable on the clamp screw, whereby it is secured to the holder, so that its degree of inclination can 60 be arranged to bring its point in line with the axis of the handle, and to cause its interior surface to approximate more or less the looper blade, which is made broad enough to have its edges engage or nearly engage the 65 sides of such interior surface. So that the

yarn or strip of rag can be easily threaded along the blade, and when threaded is not liable to escape the end of the looper blade in its action. And as the presser arm is offset and the lance, looper blade and looper stem are located in line with the axis of the handle, the movement of these parts is suitably balanced for direction of operation with reference to exact work.

In order to prevent stray strands of yarn 75 from working back of the looper blade, which runs down through the lance, a slender wire 2^a is secured under the head of the clamp screw 2 and extended forward of the lance 2 where it is looped or coiled at 2^b to receive 80 the yarn.

The bearing piece 3, is located forward of the operating flange *t*, and has a lateral extension at 3^a, which projects between the branches 7 of the carrying frame, thus preventing rotary movement of the stem *d*. When the looper blade is retracted by the 85 spring *c*, its inward movement is limited by the bearing piece 3, acting as a stop, as shown.

Having described the invention, what I claim and desire to secure by Letters Patent is:

1. In a rug machine, a hollow handle, a carrying frame connected thereto, a slide device having movement over said carrying frame, and provided with an inward extending arm at its outer end, a tubular lance carried by said inward extending arm, said tubular lance being in line with the handle 95 and having an open rear end, a looper blade extending through said lance and having a stem portion extending into a hollow handle, a retracting spring for said blade located within the handle, and a catch device for 100 said blade capable of release by said slide device.

2. In a rug machine, a handle, a carrying frame connected thereto and having the body thereof offset to one side of said handle, a slide device having movement over said carrying frame, and provided at its forward end with an inward extending arm and at its rear end with an operating flange having a perforation, a tubular lance having connection at its rear end with said inward extending arm, and having an open rear end, a looper blade extending through said lance, having a stem portion engaging the perforation of said operating flange and provided 110 with a seat in the handle, said stem portion having a bearing piece located forward of the operating flange, a retracting spring for the looper blade and a catch device for said blade capable of release by said slide device. 115

3. In a rug machine, a hollow handle, a carrying frame connected thereto, a slide device having movement over said carrying frame, an inward extending arm at its outer end, and an operating flange at its inner end, 120

a tubular lance carried by said inward extending arm, in line with the handle and having an open rear end, a looper blade extending through said lance and having a stem portion extending into the hollow handle, a 5 retracting spring for said blade located within the handle, and a catch device for said blade capable of release by said slide device.

4. In a rug machine, a hollow handle, a 10 bracket upon said handle, a carrying frame having spring branches connected to said bracket, and a presser foot, a slide device having movement over said carrying frame, an inward extending arm at its outer end, 15 and an operating flange at its inner end provided with a perforation, a tubular lance carried by said inward extending arm, in line with the handle and having an open rear end, a looper blade extending through said lance 20 and having a stem portion extending through the perforation of the operating flange into the hollow handle, a retracting spring for said blade located within the hollow handle, and a spring catch device for said looper 25 blade capable of being released by said operating flange.

5. In a rug machine, a handle having a bracket, a carrying frame having spring branches connected to said bracket, said 30 branches having outward deflected portions terminating in a presser foot, a slide device having movement over said carrying frame and having an inward extending arm at its outer end, a tubular lance carried by said 35 inward extending arm, in line with the handle and having an open rear end, a looper blade extending through said lance, a retracting spring for said blade, a spring catch device for said blade capable of release by 40 said slide device, and an outward extending loop arm for the yarn, carried by said slide device.

6. In a rug making machine, the hollow handle, its spring and cap, in combination with a looper stem reciprocating in said 45 handle, its catch spring, a reciprocating lance frame, and a deflecting arm carrying a presser foot.

7. A rug machine, consisting of a hollow handle, its spring and cap, a reciprocating 50 stem in said handle having a catch spring, a bearing piece on said stem, an offset presser arm secured to said handle, a reciprocating lance holder having a finger piece, an adjustable open end tubular lance, and a looper 55 blade extending from said stem into said lance.

8. In a rug machine, a handle, a carrying frame connected thereto and having the body thereof offset to one side of said handle, 60 a slide device having movement over said carrying frame, and provided at its forward end with an inward extending arm, and at its rear end with an operating flange having a perforation, a tubular lance having connection 65 at its rear end with said inward extending arm, and having an open rear end, a looper blade extending through said lance, and having a stem portion engaging the perforation of the operating flange and provided 70 with a seat in the handle, said stem portion having a bearing piece located forward of the operating flange and provided with a lateral extension having engagement with said carrying frame to prevent rotary movement 75 of the stem portion, a retracting spring for the looper blade and a catch device for said blade capable of release by said slide device.

In testimony whereof I affix my signature, in presence of two witnesses.

JOHN E. GARRETT.
